US00D630739S

(12) **United States Design Patent**
Tenger et al.

(10) **Patent No.:** US D630,739 S
(45) **Date of Patent:** ** Jan. 11, 2011

(54) **LARYNGOSCOPE BLADE**

(75) Inventors: **James P. Tenger**, Carlsbad, CA (US);
Leslie A. Tenger, Carlsbad, CA (US);
John R. Hicks, Carlsbad, CA (US)

(73) Assignee: **Intubrite, LLC**, Vista, CA (US)

(**) Term: **14 Years**

(21) Appl. No.: **29/352,457**

(22) Filed: **Dec. 21, 2009**

(51) LOC (9) Cl. **24-02**

(52) U.S. Cl. **D24/137**

(58) Field of Classification Search D24/137,
D24/133, 135, 138; D8/34, 40; 600/185–200;
606/191–200

(57) **CLAIM**

The ornamental design for a laryngoscope blade, as shown and described.

DESCRIPTION

FIG. 1 is a perspective view of a laryngoscope blade.

FIG. 2 is a top plan view of the laryngoscope blade.

FIG. 3 is a rear elevational view of the laryngoscope blade.

FIG. 4 is a right side elevational view of the laryngoscope blade.

FIG. 5 is a left side elevational view of the laryngoscope blade.

FIG. 6 is a bottom plan view of the laryngoscope blade; and,

FIG. 7 is a front elevational view of the laryngoscope blade.

The broken lines shown in FIGS. 1-7 are included for the purpose of illustrating environmental elements only and form no part of the claimed design.
